UNITED STATES PATENT OFFICE.

SAMUEL WESTFALL, OF THAYER, MISSOURI.

ROTARY ENGINE.

SPECIFICATION forming part of Letters Patent No. 470,405, dated March 8, 1892.

Application filed May 25, 1891. Serial No. 393,978. (No model.)

To all whom it may concern:

Be it known that I, SAMUEL WESTFALL, a citizen of the United States, residing at Thayer, in the county of Oregon and State of Missouri, have invented a new and useful Rotary Engine, of which the following is a specification.

This invention relates to rotary engines; and it has for its object to provide a machine of this class which shall be simple in construction and by the use of which the greatest amount of power may be derived in proportion to the consumption of steam.

The invention consists in the improved construction, arrangement, and combination of parts, which will be hereinafter fully described, and particularly pointed out in the claims.

In the drawings hereto annexed, Figure 1 is a side view of a rotary engine constructed in accordance with my invention, the near side of the casing having been removed to expose the interior construction. Fig. 2 is a longitudinal vertical sectional view. Fig. 3 is a horizontal sectional view taken on the line 3 3 of Fig. 1. Fig. 4 is a perspective detail view of the parts constituting one of the sliding self-packing pistons.

Like numerals of reference indicate like parts in all the figures.

The casing of my improved rotary engine is oblong in shape and is provided with bearings for the transverse shafts 1 1, upon which the cylinders 2 2 are mounted. Although described as "cylinders," the parts 2 2 are not, preferably, cylindrical in shape, but consist of star-shaped wheels, as clearly shown in Figs. 1 and 2 of the drawings, the projecting arms 3 3 of said wheels being rounded, so as to engage or mesh with each other like a pair of cog-wheels. The shape of these so-called "cylinders," however, may be modified in numerous ways without departing from my invention. In describing my invention, however, I shall refer particularly to the construction shown in Figs. 1 to 4, inclusive.

The casing of the engine is provided at one side with ports or openings 4 for the admission of steam, and the bottom of the casing 5 has a recess 5, constituting the steam-chest, and provided with a central ridge 6 and with

pockets or concavities 7, which equalize the steam between the last two pistons that have just left the steam-chest and the pressure in the chest itself, the purpose of which will be 55 hereinafter further described. The upper outer corners of the casing are provided with eccentric recesses 8 to admit of the expansive action of the steam. The upper portion of the casing has the exhaust-chamber 9 and exhaust-port 10. The sides of the casing, at both sides of the exhaust-chamber, have the depending lips 11, which are concentric with the shafts 1 1 and which serve to guide the radially-sliding pistons in the latter, as will 60 be hereinafter described. The portions of the casing between the steam-chest 5 and the eccentric recesses 8, are concentric with the shafts 1 1. Between the lips 11 is hinged a guide 12^b to guide the radially-sliding pistons 70 over the sharp point of contact upon leaving said depending lips.

The arms 3 3 of the cylinders are provided with transverse slots 12 at their outer ends, and the sides of said arms are provided with 75 recesses, which are of greater width than the said slots and which are provided near their outer ends with shoulders 14. Recesses, as 15, are also formed in the sides of the arms at the outer ends of the latter. In each of the 80 slots 12 is fitted a compound piston composed of two plates 16, each of which is provided at its inner end with a slot 17 to accommodate a rib 18, which is formed in the meeting face of the opposing-plate. The said plates are provided with inwardly-extending arms 19, extending into the recesses 13 and provided with heads 20 at their inner ends to engage the shoulders 14, so as to prevent the compound pistons from being forced out of their 85 seats in the arms of the cylinders. The outer edges of the plates 16 are provided with flanges 21 on their outer sides to overlap the outer ends of the arms 3, in which they are seated, and at their outer corners the said 90 plates are provided with lugs 22, fitted to the recesses 15. The said lugs, as well as the flanges 21, are curved or rounded, so as to engage the inner wall of the engine casing and to form a smooth bearing against the latter. 100 Cylindrical sockets or recesses 23 are formed in the arms 3 at the bottoms of the slots

to accommodate coiled spring 24, whereby the compound pistons are forced outward against the walls of the casing. Each of the arms 3 of the cylinders is provided in the side facing 5 the steam-entrance with a perforation 25, communicating with the inner end of the slot 12, so as to admit steam for the purpose of forcing the compound pistons outwardly, and thus providing tight joints. The springs 24 10 may be arranged differently from the manner herein described without departing from the spirit of my invention.

The bottom of the casing is provided with auxiliary steam ports or entrances 26, which 15 are connected by passages 27 with the eccentric recesses 8. The latter, as above stated, are provided, essentially, for the purpose of admitting of the expansion of the steam; but live steam may, when desired, be supplied 20 through the ports 26 and passages 27 when it shall be desired to gain extra power for the purpose of starting the engine or when the load to be driven is unusually heavy. An auxiliary port 4^b, worked by a try-cock, is located 25 below the port 4 to be used when the side ports are not used.

In operation the compound pistons will be forced by the action of the springs in an outward direction, so that the flanges at their 30 outer ends shall be normally in contact with the walls of the casing. When steam is admitted to the steam-chest, it will expand against the pistons which are in contact with the ridge 6 and with the concentric portion 35 of the casing between the steam-chest and the recesses 8, and the cylinders will thus be rotated in opposite directions. The pockets or recesses 5 will admit of the passage of steam to the pistons which are in contact with the 40 eccentric portions of the casing, while other pistons are in engagement with the ridge 6. Additional power will be gained by the steam expanding in the eccentric recesses 8, and the steam is finally exhausted through the chamber 45 9 and port 10, while the pistons are forced back into the recesses in the respective arms by the lips 11 at the sides of the exhaust-chamber.

It is preferred to provide the shafts 11 outside 50 the casing of the engine with gears or spur-wheels, as shown at 30 in Fig. 3 of the drawings, for the purpose of insuring an even and steady motion, and power may be taken from the said shafts in any suitable and well-known manner.

By making such modifications in the construction of the casing as will readily suggest themselves to those familiar with the art my improved engine may be made reversible; but 60 I have not deemed it necessary to illustrate such modification in the drawings hereto annexed.

In any construction of my improved engine it is obvious that the radially-sliding pistons will be forced in an outward direction 65 and held in contact with the walls of the casing, not only by the action of the spring provided for the purpose, but also by the action of centrifugal force when the engine is in operation.

Having thus described my invention, I claim and desire to secure by Letters Patent of the United States—

1. In a rotary engine, the combination, with the casing, of the revoluble cylinders having 75 radial arms or cogs meshing with each other, said arms being provided with radially-sliding piston-plates mounted in recesses formed in said arms, substantially as set forth.

2. In a rotary engine, the combination of 80 the casing, the revoluble cylinders or star-wheels having radial recesses, and the compound piston-plates seated in said recesses and adapted to engage the walls of the casing, substantially as set forth. 85

3. In a rotary engine, the combination of the casing having the steam-ports 4, the steam-chest 5, the transverse ridge 6, the expansion-recesses 8, the pockets 7, the exhaust-chamber 9, and port 10, and the depending lips 11 90 with the revolving star-wheels or cylinders having the radially-sliding compound pistons and the springs to force the latter in an outward direction, substantially as set forth.

4. In a rotary engine of the class described, 95 the combination of the cylinders having transverse slots 12, recesses 13, provided with shoulders 14, and recesses 15, with the compound pistons composed of the plates 16, having slots 17, ribs 18, arms 19, provided with heads 20, 100 flanges 21, and lugs 22, and springs arranged to force the said compound pistons in an outward direction, substantially as and for the purpose set forth.

5. In a rotary engine, the combination of 105 the casing having the steam-ports 4, the steam-chest 5, the transverse ridge 6, the expansion-recesses 8, the pockets 7, the exhaust-chamber 9, and port 10, and the depending lips 11 with the revolving star-wheels or cylinders 110 having the radially-sliding compound pistons, the springs to force the latter in an outward direction, and the guide 12^b, hinged between the lips 11, substantially as set forth.

In testimony that I claim the foregoing as 115 my own I have hereto affixed my signature in presence of two witnesses.

SAMUEL WESTFALL.
